UNITED STATES PATENT OFFICE.

JULIUS KOPEC, OF FRANKFORT HEIGHTS, ILLINOIS.

ENVELOP AND PROCESS OF MAKING AND SEALING THE SAME.

1,294,481.

Specification of Letters Patent.

Patented Feb. 18, 1919.

Application filed March 18, 1918. Serial No. 223,166.

To all whom it may concern:

Be it known that I, JULIUS KOPEC, a citizen of the United States, residing at Frankfort Heights, in the county of Franklin and 5 State of Illinois, have invented certain new and useful Improvements in Envelops and Processes of Making and Sealing the Same; and I do declare the following to be a full, clear, and exact description of the invention, such as will enable others skilled in the art to which it appertains to make and use the same.

This invention relates to envelops, and it more specifically relates to what may be 15 termed a multi-seal message packet.

One of the objects of this invention is to provide an envelop that cannot be opened without detection.

Another object is to provide an envelop 20 that protects the letter or other inclosure against unauthorized observation through the envelop.

Another object is to provide a device of 25 this character that protects the inclosures against damage by external and contiguous mail matter, by the several thicknesses of paper that constitute its inner and outer and intermediate walls.

Another object is to provide an envelop 30 of this character that is light in weight so as not to increase the postage beyond that which applies to ordinary envelops.

Another object is to provide a message 35 packet in which envelop and letter sheet are folded together in a manner to prevent unauthorized inspection without irreparable mutilation of the envelop and letter sheet.

Other objects and advantages may become 40 apparent to persons who read the following details of description in connection with the accompanying drawings in which:—

Figure 1 is a plan view of the paper blank from which my improved envelop is formed;

Figs. 2, 3, 4, 5 and 6 are perspective views 45 of the blank in the successive stages of the folding or forming operation;

Figs. 7, 8, and 9 are perspective views of the finished envelop in the several stages of the closing and sealing operation;

Fig. 10 is a perspective view of the finished envelop open to receive the letter;

Fig. 11 is a perspective view of the envelop ready for mailing; and

Fig. 12 is a sheet of writing paper especially designed or creased for folding to fit

within this form of envelop, and which may be combined with this envelop to constitute an improved means for the safe and secret transmission of messages.

Referring to these drawings in detail, in which similar reference characters correspond with similar parts throughout the several views, it will be seen that the blank (as shown in Fig. 1) is divided into squares and half-squares or triangles. There are three 60 squares 1, 2 and 3, respectively arranged corner to corner in the median line of the blank. These squares each remain unfolded at all times and are hereinafter referred to as the non-folding squares or quadrangles. 65 There are four squares 4, 5, 6 and 7, respectively, whose inner boundary lines coincide respectively with the boundary lines of the middle square 2. There are four triangles, 70 8, 9, 10 and 11, respectively, and the bases of these triangles combine to form parallel 75 outer edges of the blank. The broken lines across the blank define the internal boundaries of said squares and triangles, and along these broken lines the blank is folded in 80 forming and sealing the envelop.

This envelop may be described with greater clearness by first defining the successive steps or stages in the process of making it, which is as follows:—

The blank is first folded along the line *a*—*b* (see Figs. 2 and 3) so that the squares 1 and 2 are now in superposed relation to one another and the squares 4 and 5 are folded on themselves so that the triangular 90 halves of each of these squares are in superposed relation to one another, as shown in Figs. 3 and 4. The blank is next folded along the lines *c*—*e* and *d*—*e*, as shown in Figs. 4 and 5, so that the previously folded 95 squares 4 and 5 are now in superposed relation to the previously superposed squares 1 and 2. The blank is next folded along the lines *k*—*m* and *l*—*m* so as to bring the triangular flap 8 into superposed relation to 100 the superposed elements 1, 2 and 4, and to bring the flap 9 into superposed relation to the elements 1, 2 and 5. The flaps 8 and 9 are of a size and shape to interlap with one another, as shown at 12 in Figs. 6 and 7, and 105 these flaps are each provided with an adhesive coating 13 whereby they unite the meeting edges of the elements 4 and 5 (Fig. 5) and also unite with one another at their interlapped edges. When these elements 110

are thus united, the envelop is completely formed, and it is now made complete by the application of an adhesive coating 14 along the outer edges of the sections 3, 6 and 7 5 (which constitute the main closure flap of the envelop), and by applying an adhesive coating 15 to the element 1 (which constitutes the auxiliary or outer closure flap.)

Fig. 10 shows an opening extending from 10 *c* to *d* and constituting the entrance to a triangular pocket 16 that receives the letter-sheet, or any similar inclosure, and the latter may be either square or triangular, the latter being preferable for the sake of perfect 15 security against unauthorized inspection, as will appear hereinafter. Referring to Fig. 12, it will be seen that when this sheet of paper is folded along the broken line that extends from corner to corner, it is made triangular, so that its rectangle may fit the lower part of the envelop, while its acute angles are disposed at the respective points *c* and *d*, and the main flap may now be turned into closing position by folding the 20 envelop along the lines *c-d* to bring the points *e* and *f* into registry and contact, as shown in Figs. 7 and 8, and the envelop is now singly-sealed and is as safe as any ordinary envelop; but, in order to render the 25 envelop super-safe, it is again folded and 30 again sealed. This is effected by folding the letter-sheet and the envelop together, the latter being folded along the fold lines or creases *g-h* and *g-i* which now coincide 35 respectively with the fold lines *k-m* and *l-m* (see Figs. 7 and 8). In thus re-sealing or double-sealing the envelop, the adhesive 40 coated ends of the flaps 6 and 7 are inserted between the elements 1 and 2, as shown in Fig. 9, and the auxiliary sealing flap part of the element 1 is then secured to these elements 6 and 7 by means of the adhesive coatings 15 and 17 (see Figs. 8 and 9).

45 The process in brief, consists in securing a message against undetectable inspection by (1st) providing a letter-sheet bearing the message, (2nd) providing a foldable envelop with a pocket and with a pocket-closing flap and with a sealing flap, (3rd) placing the letter-sheet in said pocket, (4th) closing said pocket with said pocket-closing flap, (5th) folding said pocket and the inclosed letter-sheet, and (6th) sealing the 50 envelop and letter-sheet in their folded relation by means of said flap.

It will be seen, therefore, that the envelop is not only double-sealed, but that the letter-sheet is folded with the envelop prior to the 55 final sealing step, and that the letter-sheet can not be removed from the envelop after merely slitting the latter along any one or more of its edges; but, in order to gain access to the letter-sheet so as to read its contents, the envelop and letter-sheet must first

be unfolded, and this can only be done by mutilating the flap or element 1. After unfolding the envelop and letter-sheet, the unfolded envelop shown in Fig. 8 may then be slit along either edge so as to gain access 70 to the letter-sheet; but by merely disengaging the adhesive 14 along one edge, the letter sheet can not be removed from and replaced in the envelop so as to avoid detection of the fact that the letter or message has been tampered with. 75

In order that this envelop may be as light as possible, consistent with strength, and in order that it may not be opened without mutilation, I prefer to make it of very thin 80 paper such as tissue or semi-tissue paper. As the folded and sealed envelop protects the inclosure by at least three thicknesses or walls of the envelop, the message is more fully protected from inspection than if 85 shielded by only one thickness of thicker paper.

From the foregoing it will be seen that this form of envelop and message packet is of exceptional importance in time of war for 90 transmitting messages from one officer to another, for it insures that the message has not been also transmitted to the enemy by an unfaithful messenger. This envelop will also be appreciated by all persons who wish 95 their messages preserved in perfect secrecy.

It is to be understood that my invention is not limited to the exact details as herein described, but that minor changes may be made within the scope of the appended 100 claims.

What I claim as my invention is:

1. An envelop formed with a pocket having corners, a sealing flap movable into superposed relation with one side of the pocket 105 and provided with means for securing it in said relation; a sealing flap on the opposite side of said pocket, said pocket having fold-lines along which the pocket and the first said flap may be folded, said fold-lines being arranged so as to allow two corners of said pocket to be inserted between the body of the envelop and the second said flap; and means for securing the second said flap to 110 said corners. 115

2. An envelop formed with a triangular pocket, a sealing flap movable into superposed relation with one side of the pocket and provided with means for securing it in said relation; a sealing flap on the opposite 120 side of said pocket, said pocket having fold-lines along which the pocket and the first said flap may be folded, said fold-lines being arranged so as to allow two corners of said triangular pocket to be inserted between the body of the envelop and the second said flap; and means for securing the second said flap to 125 said corners.

3. In combination a letter-sheet, a pocket containing said letter-sheet and having ends 130

folded with said letter-sheet against the intermediate part of the pocket, a flap closing said pocket and folded therewith and with said letter-sheet, a second flap overlapping the folded ends of the pocket, and means for securing said second flap to said folded ends.

5 In testimony whereof I have hereunto set

my hand in the presence of two subscribing witnesses.

JULIUS KOPEC.
